UNITED STATES PATENT OFFICE.

JOHN W. FULLER, OF DALTON, MASSACHUSETTS, ASSIGNOR OF THREE-FOURTHS TO HUGH F. WARD AND HENRY A. BARTON, OF SAME PLACE, AND JACOB E. ACKERMAN, OF BOSTON, MASSACHUSETTS.

DESIGN FOR A CUTTING-BLADE.

SPECIFICATION forming part of Design No. 32,191, dated February 6, 1900.

Application filed January 5, 1900. Serial No. 517. Term of patent 14 years.

To all whom it may concern:

Be it known that I, JOHN W. FULLER, a citizen of the United States, residing at Dalton, in the county of Berkshire and State of Massachusetts, have invented and produced a certain new and original Design for a Cutting-Blade, of which the following is a specification, reference being had to the accompanying drawings, forming a part thereof.

Figure 1 is a perspective view of a cutting-blade, illustrating my design; and Fig. 2 is a sectional detail, the section being taken in the line 2 2, Fig. 1.

The leading feature of my design for a cutting-blade consists in a body portion beveled along one edge and abruptly upturned or deflected at one end thereof.

The blade is shown as consisting of a body portion A, the front edge of which is beveled, as at 2, the beveled edge being abruptly upturned at one end of the body, as at 3, on a very short radius, and the whole presenting a pleasing and graceful design. 20

Having thus described my design, what I claim is— 25

The design for a cutting-blade, substantially as shown and described.

In testimony whereof I have signed my name to this specification in the presence of two subscribing witnesses.

JOHN W. FULLER.

Witnesses:

GEO. W. GREGORY,
MARGARET A. DUNN.
